REFRIGERATING MACHINE

Application filed March 8, 1932, Serial No. 597,456, and in Switzerland August 17, 1931.

This invention relates to refrigerating machines and is particularly concerned with machines as described in U. S. application Ser. No. 451,933 filed May 13th 1930. The object of the invention is to provide an improved means for automatically returning from the evaporator to the compressor of a refrigerating machine oil used for lubrication and sealing the clearances of the moving parts. For this purpose the chamber which is maintained at a lower pressure than the evaporator and to which the discharge pipe of the oil accumulator is connected, constitutes the suction chamber of an injector 15 which is operated by the refrigerating medium supplied to the compressor.

According to the present invention the cross-sectional area of the admission nozzle of the injector is adjustable for the purpose of varying the suction in the oil discharge pipe in accordance with the working conditions in the machine. Conveniently a tapered needle is mounted adjacent the nozzle so that it is movable in the direction of 25 the nozzle axis and it tapers in the direction of the flow through the nozzle.

Preferably the position of the needle is automatically controlled by the admission pressure of the refrigerating medium supplied from the evaporator. The needle may be mounted on a movable member which is actuated in accordance with the difference between this admission pressure and the atmospheric pressure or the pressure of the refrigerating medium in the condenser or the pressure on the outlet side of the admission nozzle. Conveniently the needle is mounted on a movable piston-like member the two sides of which are respectively exposed to the two controlling pressures. The initial setting of the needle may be varied by adjusting by hand the tension of a spring 40 acting on the movable member carrying the needle.

If desired, instead of automatically controlling the position of the needle in accordance with the admission pressure, it may be controlled by a thermostat or other temperature responsive device associated with the 45 evaporator so that the cross-sectional area

of the admission nozzle is varied in accordance with the evaporator temperature.

Several constructions of injector for refrigerating machines in accordance with this invention will now be described by way of 55 example with reference to the accompanying drawings.

Fig. 1 shows a refrigerating plant according to the invention diagrammatically.

Figures 2 to 5 show different constructions 60 of the injector in sectional side elevations.

In Figure 1 the refrigerating medium is supplied to the compressor C by the pipes c—e from the evaporator E. The evaporator has an oil collector A, from which oil 65 is discharged through the pipe d. This discharge pipe d opens into the suction chamber of an injector a, b which is so connected to the suction pipe e of the compressor C that it is operated by the refrigerating medium. Oil collecting in the collector A is thus drawn up into the suction chamber of the injector a, b without appreciable loss of pressure of the refrigerating medium and is carried away by the rapidly moving refrigerating medium and returned to the 70 compressor in an atomized state. 75

In the injector shown in Figure 2 the refrigerating medium from the evaporator passes from pipe e through the admission 80 nozzle a and the mixing nozzle b to the pipe e which is connected to the compressor of the machine. The oil discharge pipe d from the oil collector is connected to the injector on the outlet side of the admission nozzle a. 85

A tapered needle g is mounted on a piston-like member k, which moves in a cylinder formed in the casing f of the injector, so that the needle is tapered in the direction of the flow of the refrigerating 90 medium from the pipe e through the admission nozzle a. Thus by adjusting the position of the piston k the needle g is moved along the axis of the nozzle a and acts to vary the effective cross-sectional area of this 95 nozzle.

The upper side of the piston k is connected to the top of the injector casing by a flexible corrugated diaphragm h which does not prevent the free movement of the 100

piston but which acts to maintain an air tight joint between the piston and the casing so that the refrigerating medium cannot escape from the casing on the upper side of the piston. The upper side of the piston *k* is exposed to atmospheric pressure by means of a duct *f*¹ in the top of the casing which communicates with the inside of the flexible diaphragm *h*. In order to control the initial setting of the needle *g* of the piston a spring *i* is arranged between the upper side of the piston *k* and a plug *l* which is mounted in the top of the casing so that it can be rotated by hand to vary the tension of the spring *i* by means of a key which fits within a square or rectangular recess in the top thereof.

When the refrigerating machine is started the pressure in the evaporator will usually be high and the refrigerating medium drawn into the injector will thus be comparatively heavy so that the effective weight of the medium passing through the admission nozzle past the end of the oil pipe will be comparatively large. Under these conditions the kinetic energy of the refrigerating medium in the admission nozzle will be sufficient for inducing in the pipe *d* a suction pressure which is lower than that in the pipe *c* and is quite sufficient for pumping the oil from the collector into the injector and thence back to the compressor. When the machine has been working for an appreciable time the evaporator pressure will decrease with the result that the refrigerating medium or vapour drawn in will become lighter. The kinetic energy of this vapour in the admission nozzle is thus reduced and may even decrease to such a value that it is insufficient for pumping any oil.

This decrease in the effective weight of refrigerating medium passing through the admission nozzle is, in accordance with the present invention, compensated for by decreasing the area of the nozzle so as to maintain the kinetic energy at the desired value.

When the admission pressure decreases the piston *k* moves downwards thus reducing the cross-sectional area of the admission nozzle and consequently increasing the kinetic energy of the vapour passing through the nozzle. The tension of the spring *i* is set by adjusting the screw plug *l* so that the piston *k* moves to adjust the position of the needle *g*, in accordance with changes in the pressure of the refrigerating medium pumped from the evaporator, to maintain the kinetic energy of the vapour passing through the admission nozzle *a* at substantially the correct value for pumping the requisite quantity of oil irrespective of changes in the operating conditions of the machine.

In the modified construction shown in Figure 3 the upper side of the piston *k* is

formed as a cylinder for another piston *p* the upper side of which is connected by a corrugated flexible diaphragm *n*, similar to the diaphragm *h*, to a screw plug *q* in the top of the injector having an aperture connected by a pipe *c* to the condenser of the machine. The upper side of the piston *p* is thus exposed to the condenser pressure the sleeve *n* furnishing a gas tight joint between the plug *q* and this cylinder. A spring *m* is arranged between the upper side of the piston *k* and the under side of the piston *p* so that movements of the piston *p* due to variations in the pressure in the condenser are communicated to the piston *k* through this spring, the initial tension of the spring *m* being adjusted by varying the position of the screw plug *q*.

It will be apparent that this modified arrangement acts in a manner similar to that shown in Figure 2 with the exception that the movements of the piston *k* are controlled in accordance with variations in the difference between the pressures of the refrigerating medium from the evaporator admitted through the pipe *c* and the pressure in the condenser.

In the construction shown in Figure 4 the upper surface of the piston *k* is connected through a duct at the top of the injector casing and a pipe *r* to the oil supply pipe *d* near the point at which it is connected to the injector casing. The piston *k* is thus controlled in accordance with variations in the difference between the pressure of the refrigerating medium drawn from the evaporator and the pressure on the outlet side of the admission nozzle. It is to be noted that as the pressure on the outlet side of the nozzle increases due to the decrease of the kinetic energy in the nozzle the piston *k* moves downwards thus decreasing the area of the nozzle so that the kinetic energy in the nozzle is again raised to the required value.

This construction also differs from the arrangement shown in Figure 2 in that the tension of the spring *i* is adjusted by a screw plunger *l* the stem of which passes through a stuffing box *s*. A screw cap *t* is provided for the top of the recess in the casing into which the plunger *l* fits so as to ensure an air tight joint in the part of the casing above the piston *k*.

In the construction shown in Figure 5 the needle *g* constitutes the lower end of a rod *x* which is mounted in a bearing carried by the casing *f* so that it is coaxial with the admission nozzle *a*. The upper end of the rod *x* is connected by links to the rod of a piston *w* mounted on a flexible diaphragm *v* one end of which is connected to the casing *f* and the other end to the piston *w*. The interior of the diaphragm *v* communicates, by means of a pipe *u*, with a temperature responsive device such as a thermostat (not

shown) which is arranged on or in the neighbourhood of the evaporator. The diaphragm *v* thus expands or contracts in accordance with changes in the temperature 5 of the evaporator, the movement of the diaphragm causing corresponding movement of the piston *w* and thus, through the link mechanism and rod *x*, of the needle *g*.

It will be appreciated that the above description is by way of example only and that detailed modifications may be made in the construction and arrangement of the injector within the scope of this invention.

I claim:

1. A refrigerating machine, comprising a main evaporator, a compressor, and a means between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector 25 to the suction chamber of said injector, a pipe leading from the pressure chamber of said injector directly to the compressor, the cross-sectional area of the admission nozzle of the injector being adjustable for the purpose of controlling the suction in the oil discharge pipe in accordance with the working conditions in the machine.

2. A refrigerating machine, comprising a main evaporator, a compressor, and a means 35 between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading 40 from the pressure chamber of said injector directly to the compressor, the cross-sectional area of the admission nozzle of the injector being adjustable for the purpose of controlling the suction in the oil discharge pipe in accordance with the working 45 conditions in the machine, said nozzle having a needle-member therein, to control the cross-sectional area thereof, said member being tapered in the direction of flow through the nozzle.

3. A refrigerating machine, comprising a main evaporator, a compressor, and a means 55 between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe

leading from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein to control the cross-sectional area thereof, said member being tapered in the direction of flow 70 through the nozzle, and being movable in the direction of the nozzle axis.

4. A refrigerating machine, comprising a main evaporator, a compressor, and a means 75 between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading 80 from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow 85 through the nozzle, and means for automatically varying the position of said needle in accordance with variations in the pressure of the refrigerant admitted thereto.

5. A refrigerating machine, comprising a main evaporator, a compressor, and a means 90 between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading 95 from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow 100 through the nozzle, and means for automatically varying the position of said needle in accordance with variations in the pressure of the refrigerant admitted thereto.

6. A refrigerating machine, comprising a main evaporator, a compressor, and a means 105 between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading 110 from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow 115 through the nozzle, and means for automatically varying the position of said needle in accordance with the difference between the pressure of the refrigerant admitted thereto and that of the atmosphere.

6. A refrigerating machine, comprising a main evaporator, a compressor, and a means 120

between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle member therein, to control the cross-sectional area thereof, said member being tapered in the direction of flow through the nozzle, and means for automatically varying the position of said needle in accordance with the difference between the pressure of the refrigerant admitted thereto from the evaporator and that of the refrigerant in the condenser.

7. A refrigerating machine, comprising a main evaporator, a compressor, and a means between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow through the nozzle, and means for automatically controlling the needle in accordance with the difference in pressure between the pressure of the refrigerant admitted thereto and the pressure on the outlet-side of the nozzle.

55 8. A refrigerating machine, comprising a main evaporator, a compressor, and a means between the evaporator and the compressor for returning the lubricant and the refrigerant from said evaporator directly to said compressor and including an injector having 60 a pressure chamber and a suction chamber, a lubricant collector for collecting by gravity lubricant from the refrigerant, a discharge pipe connecting the said collector to the suction chamber of said injector, a pipe leading 65 from the pressure chamber of said injector directly to the compressor, the cross-

sectional area of the admission nozzle of the injector being adjustable for the purpose of controlling the suction in the oil discharge pipe in accordance with the working conditions in the machine, said nozzle having a needle therein, said needle being mounted on a movable, piston-like member, said member having two faces respectively exposed to the two operating pressures. 70

9. A refrigerating machine, comprising a main evaporator, a compressor, and a means between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow through the nozzle, a movable member for carrying the needle, a spring acting thereon, and means for manually adjusting the effective-force of said spring to effectuate the initial setting of said spring. 100

10. A refrigerating machine, comprising a main evaporator, a compressor, and a means between the evaporator and the compressor for returning the lubricant and the refrigerant from said evaporator directly to said compressor and including an injector having a pressure chamber and a suction chamber, a lubricant collector for collecting by gravity lubricant from the refrigerant, a discharge pipe connecting the said collector to the suction chamber of said injector, a pipe leading from the pressure chamber of said injector directly to the compressor, the cross-sectional area of the admission nozzle of the injector being adjustable for the purpose of controlling the suction in the oil discharge pipe in accordance with the working conditions in the machine, said nozzle having a needle-member therein, to control the cross-sectional area thereof, said member being tapered in the direction of flow through the nozzle, and a temperature-responsive device operatively connected to the evaporator, said device being connected to said needle so as to control the position of same in accordance with the temperature of the evaporator. 105 110 115 120 125

In testimony whereof I affix my signature.

EMIL KÄGL.
